UNITED STATES PATENT OFFICE.

JAMES LEWIS KIMBALL, OF SALEM, MASSACHUSETTS, ASSIGNOR TO RUGGLES-KLINGE-MANN MFG. CO., OF SALEM, MASSACHUSETTS.

DAMPER REGULATOR.

Application filed April 5, 1920. Serial No. 371,548.

My invention relates to regulators, and more particularly to damper regulators in which the air supply to the furnace is regulated by the pressure in the boiler. Among 5 the objects of the invention are to remove all possible friction from the scale beam and thereby produce a more sensitive regulator, to effect a graduated movement of the plunger and to prevent fluctuation or hunting action.

Prior to the present invention, there were—and there still are—two types of draft regulators in use. The first and earlier is known as the dead-open-and-dead-shut type. 15 The second and later is known as the floating type. The dead-open-and-dead-shut regulator, as its name implies, operates the damper all the way from the completely open position to the completely closed position, and back again, in endless cycles. This is hunting action of an extreme type. Let it be assumed, for example, that the damper is initially placed in mid position, corresponding to a normal, average steam pressure, and that the pressure starts to decrease. The damper will start to open further. For reasons presently to be explained, it will swing wide open. This greatly increases the draft, tending to correct the decreased pressure; but the increase is much too rapid, with resulting overcorrection. The pressure thus builds up to a value much too high. Thereupon, the damper starts to close and will, in fact, as will presently be made clear, swing all the way back to the dead-shut position. The draft becomes thus completely shut off. The steam pressure should, theoretically, therefore start decreasing. As a matter of fact, it continues to rise for a time, however, because the furnace has been forced beyond what is required to support the boiler load. When the steam pressure does, ultimately, start to decrease, it has attained a value much higher than the setting of the regulator, and with an extreme furnace condition. The pressure will, therefore, now be caused to decrease to a value much too low, whereupon the damper starts to open. As the furnace has been deprived of air for some time, it can not instantly respond to the draft thus admitted, so that the damper continues in its opening movement and is soon carried over again to the extreme open position, producing an excess of air again. The damper is thus always

maintained in an extreme position, resulting either in an excess or a deficiency of air supply, as the case may be. Occasionally, under extraordinary conditions, the damper is checked in an intermediate position, and its movement reversed before a complete stroke has been made, but this is most unusual. The usual operation is by complete strokes, back and forth between the dead-open and the dead-shut positions.

To each particular value of the steam pressure there corresponds a certain particular position that the damper should occupy. With the damper in this position, the draft to the furnace will be such as to tend to maintain the steam at the corresponding pressure value. When there is a change in steam pressure due, for example, to a change in load, the damper should be moved to the position corresponding to the new value of the steam pressure. The trouble with regulators of the dead-open-and-dead-shut type is that the damper does not stop in the position corresponding to the new pressure value, but travels beyond to either the dead-open or the dead-shut position, as the case may be.

Floating-type regulators move the damper part way only, and not all the way. Theoretically, a small change in pressure conditions will cause a small movement of the damper to a position corresponding to the changed pressure value. A large change in pressure conditions will similarly cause a large movement of the damper. As these changes are continually going on, the damper is continually moving or "floating." The floating type of regulator in common use comprises a regulating motor and an element for controlling the position and the direction of operation of the motor. The motor may be hydraulic, electric, and the like, and the element may be a pilot valve, a pilot switch, or some other mechanism. The element usually has a neutral position, in which the motor is maintained against operation, and two effective positions, in which it controls the operation of the motor in opposite directions. A change in the normal conditions causes the element to be moved out of its neutral position, into one of the effective positions, and this, in turn, causes the motor to operate in the proper direction to cause a return to the normal conditions. When the regulating motor commences to

operate, it actuates a compensating device for returning the element to the neutral position.

Floating regulators, though a great improvement over regulators of the dead-open-and-dead-shut type, also hunt; for they, too, move the damper to a position beyond what is required by the changes in pressure. In the case of hydraulic motors, for example, this is caused largely by the pilot valve sticking or binding, by friction. This frictional binding it is impossible, in practice, to avoid. The compensating device must, therefore, overcome this frictional, binding action before it can begin to operate to return the valve stem to its neutral position, with the result that the motor plunger has meantime travelled too far, and caused over-correction.

With the damper in mid-position, for example, let it be assumed that the steam pressure starts to decrease. The damper is thereupon floated toward the extreme open position, increasing the draft to the furnace. Theoretically, the damper should stop at a position such that the resulting draft will just balance the decreased value of the pressure. But the damper does not stop there; it travels on beyond that point—not to the extreme open position, but a considerable distance beyond where it should have stopped. In technical language, it hunts. The damper having travelled too far in this direction, the pressure builds up to a value much too high. Thereupon the damper is floated in the reverse direction, but again too far, and again with consequent over-correction, this time in the opposite direction. The action of the regulator, therefore, is such that the damper continually overtravels, that is, hunts, in opposite directions. There is thus a continual and unnecessary reversal of the boiler operations.

According to the present invention, the compensating device is not permitted to act continuously,—as is the case with floating regulators,—but intermittently only. The motor plunger is provided with a graduated, or step-by-step, movement, and a similar action is thus transmitted to the compensating device. Each step of the operation of the motor is normally well defined, and no cut-off is possible under normal operating conditions between the cut-off points at the beginning and the end of each step. The regulator of the present invention resembles the floating-type regulator in that the damper is moved part way only, and not to its extreme positions, but it is differentiated from the floating-type regulator in that the damper does not float, but is moved by steps in response to large variations in pressure, and is normally stopped at the end of each normal step to await a further comparatively large variation in pressure before it is moved again. As the operation of the motor plung-

er is definitely terminated, and the plunger forced to come to rest, at the end of each step, overtravel of the plunger, and consequent fluctuation or hunting action, is eliminated.

To accomplish these objects, I have produced, according to the specific embodiment of the invention that is herein illustrated and described, a regulator in which the pilot valve is operated by electric magnets, using a pressure circuit closer for making an electric contact to operate the magnets. Heretofore, it was customary to connect the pilot valve direct to the scale beam, but the friction necessary to operate the pilot valve was such as to interfere with the close regulation of the steam pressure.

In the accompanying drawings, illustrating one embodiment of the invention, Fig. (1) is a vertical view, a part of which is in section; and Fig. (2) is a vertical section of the pilot valve with its operating mechanism, removed from the regulator. Like numerals refer to similar parts in the various views.

A diaphragm (1), diaphragm chamber (2), pressure cap (3), scale beam (4), and weights (5) constitute an operating device for a pressure circuit closer. The diaphragm is responsive to pressure, such as the pressure of steam from a boiler, and the chamber (2) is therefore shown connected to a source of boiler pressure at (6). Motion is imparted by the scale beam to the circuit closer mounted on the slate board by means of spindle (7). The circuit closer consists of two insulated contact points (8) and (9) which make an electric contact on opposite sides of a revolvable contact disc (27). The contact points (9) and (8) are respectively connected with electromagnets (10) and (11), of which (12) and (13) are the armatures, and (14) and (15) are the coils. Armatures (12) and (13) are connected with dashpot plungers (16) and (17) and these plungers are in turn connected to a pilot valve lever (18) at (19) and (20), respectively. The left-hand end of lever (18) is connected with pilot-valve stem (21), which fits pilot-valve body (22).

Referring more particularly to Fig. (2), the pilot valve (22) is preferably of the piston type. (34) is the inlet for water or other fluid under pressure, (35) is the waste or overflow, (33) is a passage leading to the top of the motor, and (32) is a passage leading to the bottom of the motor. The valve stem (21) is provided with cylindrical portions (38) and (39) which control the admission and exhaust to opposite ends of the motor; this stem being shown in a neutral position, in which no water can be admitted or exhausted to or from the motor cylinder. (40) is a valve bushing having an inlet (41), which admits fluid under pressure between

the two cylindrical portions (38) and (39) of the valve stem (21). When the stem is raised, water is admitted at port (42) and communicates through passage (32) to the bottom of the motor; at the same time, exhaust port (43) is opened to atmosphere, allowing water to escape from the top of the motor. When the stem (21) is lowered, admission port (42) and exhaust port (43) 5 are closed, and admission port (44) and exhaust port (45) are opened, reversing the motion of the motor. It will be understood that any pressure escaping from the top end of the motor will be exhausted to the bottom 10 end of the valve, where a cored passage on the side of the valve, not shown, allows this water to reach the top of the valve and go to waste at overflow connection (35).

It will be noted that the pilot valve stem 20 (21) normally assumes a neutral position, in which no pressure can be admitted or exhausted to or from motor cylinder (24). The pilot valve stem may also be actuated upward by one of the magnets to admit water under 25 pressure to the bottom of the cylinder, thus to effect the upward movement of the plunger (23), and downward by the other magnet, to admit water under pressure to the top of the cylinder, thus to effect the downward 30 movement of the plunger. Each dash pot and armature are of sufficient weight to hold the pilot-valve lever fulcrumed, while the opposite magnet is operated to move the valve in a certain direction.

35 The contact sheave (27) is mounted on a vertical stud (31) and is threaded to this stud with a coarse-pitch thread. It is rotatable to travel either in an upward or downward direction by the movement of the 40 motor plunger (23). After the contact has been made by the movement of the scale beam (4), the pilot valve (22) is operated to move the plunger (23) which, in turn, revolves the contact sheave (27) in the direction to break the circuit and cause the motor 45 plunger to come to rest.

The armatures being connected to oil dash 50 pots, the time required for the plungers of these dash pots to settle into their bottom position and bring the pilot valve back to its neutral position is such as to allow the motor plunger (23) to have traveled momentarily after the current has been broken. In this way, the motor plunger (23) is compelled to operate throughout a definite distance or step and the contactor disc (27) is moved to a central position half way between the contact points (8) and (9). This allows a uniform variation in pressure in either 55 direction before the contact is again made and also prevents arcing the current.

60 A definite cut-off is thus effected as soon as the circuit is broken, but the motor continues to operate between cut-off points 65 throughout a distance or step, the value of

which is determined by the time lag of the dash pot. This time lag, which regulates the return of the valve stem to its neutral position, may, of course, be adjusted to adjust the length of the steps of travel of the motor 70 plunger.

The main electric source of supply is connected at (25). This connection extends to one side of coil (14). The opposite side of the coil is connected to contact point (9) 75 through a flexible connection (36). A connection also extends from (25) to coil (15). The opposite side of this coil (15) is connected through flexible connection (30) with contact point (8). The opposite side of the 80 line (26) is connected with the screw spindle (31) on which the contact disc (27) is mounted.

The principle of the operation is as follows: The pressure of the steam in the boiler (not shown) is communicated, by way of the diaphragm chamber (2), to the flexible diaphragm (1). Variations in the steam pressure thus cause corresponding movement of the diaphragm, and this movement is 85 transmitted to the scale beam (4). As the steam pressure varies, therefore, the scale beam will be caused to pivot up and down about a knife-edge pivot or fulcrum (28). When the steam pressure in the boiler rises, the scale beam is raised, and when the steam pressure falls, the scale beam is lowered. Raising and lowering of the scale beam, if 90 effected throughout a distance corresponding to the distance separating the contact members (8) and (9) from the contact disc (27), 95 will cause operation of the motor in opposite directions. No slight fluctuation in pressure can affect the regulator. When the motor plunger (23) is raised, a weight (46) will 100 actuate the damper (47) towards closed position. When the motor plunger is lowered, it will cause corresponding actuation of the damper towards the full-open position 105 through an impelling cord (48). The motor 110 is thus automatically operated in either of its two opposite directions to operate the damper in opposite directions and thus to regulate the draft. The temperature of the furnace is therefore automatically controlled 115 to vary the steam pressure in the boiler according to the draft.

With this brief explanation of the principle of operation, the specific description that is about to follow will be readily understood. Let it be assumed that the weights (5) will just balance a normal steam pressure in the diaphragm chamber. When the steam pressure exceeds the predetermined 120 value for which the scale beam (4) is thus weighted, therefore, the scale beam will be caused to pivot upward about the pivot (28). The scale beam moves entirely independently 125 of the motor, which remains stationary until the pressure becomes sufficiently great so as 130

to cause the contact point 9 to engage the underside of the contact disc (27). A circuit is then established through the coil (14), energizing the magnet (10) to attract the armature (12). The dash-pot plunger (16) and the valve spindle (21) will therefore become raised, and fluid under pressure will be admitted, through the port (32), to the portion of the cylinder (24) under the plunger (23). The plunger (23) will then move upward, and the weight (46) will actuate the damper (47) towards the closed position, thereby shutting off, by so much, the draft to the furnace.

13. To the top of the plunger (23) is secured the upper end of a cord (29) that extends around the contact disc (27), a weight (37) being secured to the other end of the cord (29) to take up the slack therein and to provide sufficient tension in the cord to cause it to engage the contact disc firmly. As soon as the motor plunger starts its upward travel, therefore, to permit the weight (46) to actuate the damper, it effects, also, a slight 25 rotative movement of the contact disc (27) by means of the cord (29). This slight movement of the contact disc (27) is in such direction as to break contact with the contact point (9), and thus to open the circuit 30 of the coil (14). The magnet (10) becomes deenergized as soon as contact is broken between the contact point (9) and the disc (27), allowing the dash-pot plunger (16) to settle into its bottom position and the 35 spindle (21) of the pilot valve to return to its neutral position. This, in turn, results in the plunger (23) being brought immediately to rest in the position that it then occupies. But the motor can not stop moving 40 as soon as contact is broken between the contact disc (27) and the contact point (9), because the dash pot prevents the immediate return of the valve stem to the neutral position. The valve is purposely kept open for 45 a time interval by the dash pot. During this time interval, the motor completes a definite step of operation, determined as to length by the adjustment of the dash pot.

47. If the steam pressure should continue to increase, the operation will be repeated, the plunger moving up to a second stage, and so on, making from ten to twelve stops before the stroke is completed and causing corresponding actuation of the damper.

55. Whenever the steam pressure decreases, the weights (5) cause the scale beam (4) to pivot downward about the pivot (28) independently of the motor, and contact point (8) engages the top of the contact disc (27), establishing a circuit through coil (15), energizing magnet (11) and attracting armature (13); the dash-pot plunger (17) will thereupon become raised, and as lever (18) is fulcrumed on dash-pot rod (16) at (19), spindle (21) will be lowered, opening port

(33) and allowing fluid under pressure to enter the top of the cylinder (24) and force the plunger (23) downward. As the plunger moves, it actuates the damper in the opposite direction to increase the draft to the furnace. At the same time, it turns the contact disc (27), which breaks the circuit and deenergizes the magnet (11), allowing armature (13) to be released and dash-pot plunger (17) to settle into its bottom position. The pilot valve stem (21) is therefore returned to its neutral position and the plunger (23) is brought to rest, the plunger making regular stops on the downward stroke, with short periods of rest, the same as on the upward stroke. When the steam pressure rises too high, therefore, the damper (47) becomes closed by steps, in response to large variations in pressure, to shut off the furnace draft, and this permits the pressure to fall; and when the pressure falls too low, the damper is opened by corresponding steps, increasing the draft, thus again raising the steam pressure. In practice, the plunger would seldom make a complete stroke from one end to the opposite end of the motor cylinder (24), but would hold to a position in its travel which would supply the necessary air to the furnace to burn the fuel and maintain a uniform steam pressure. As changes in load or furnace conditions would take place, the plunger would move to another stage in its travel, which would correct the change and bring the steam pressure back to normal. The temperature of the furnace is thus automatically controlled to keep the steam pressure at a value approximately corresponding to the load.

In order to obtain a better understanding of the operation, let it be assumed, for example, that the mean average value of the steam pressure is 100 pounds, and that a change in load has caused the pressure to become increased to 101 pounds. Let it be assumed, further, that the regulator is adjusted to operate the damper when the pressure increases or decreases by increments of one pound. No value of the pressure between 100 and 101 pounds can, then, result in any change in the position of the damper, and the regulator will not respond to such slight changes. The scale beam will merely move up and down, but without establishing contact between the contact disc (27) and either of the contact points (8) and (9). As soon as the 101-pound value has been reached, however, the damper will suddenly be actuated one step, from the position corresponding to 100 pounds to the position corresponding to 101 pounds, and it will there be stopped and held stationary. It will not travel beyond that point, and then return, like floating regulators; that is, it will not hunt. It stops at the 101-pound point and stays there, until the pressure either

builds up to 102 pounds or falls to 100 pounds; for the contact disc (27) is always returned to a position substantially half-way between the contact points (8) and (9).

5 No change in the pressure between these values 100 and 102 can budge the damper from its 101-pound position. Should the pressure build up to 102 pounds, the damper will suddenly or abruptly be moved a second 70 step to the position corresponding to 102 pounds, and there stopped. Similarly, if the pressure should fall, instead, to 100 pounds, the damper will suddenly be returned a step 75 from the 101-pound position to the 100- 15 pound position, and there stopped. In technical language, the damper lags behind the pressure value until the pressure change reaches a point corresponding to the next stepped position. The damper is then 20 moved a whole step up to this position and stopped. In floating regulators, on the other hand, the damper floats first behind and then ahead,—it overregulates, or hunts. In the 25 regulator of the present invention, the damper can not possibly overtravel or hunt, in the one direction or the other, with the result that the boiler load or pressure is maintained approximately balanced at each stepped position until it has increased or 30 decreased sufficiently to cause actuation of the damper to a new stepped position.

Experience has shown that small variations in pressure do not ordinarily indicate either a permanently rising or a permanently falling load. If let alone, such small variations become rapidly dissipated and the pressure thus returns to normal without regulation. Floating and dead- 35 open-and-dead-shut regulators respond readily to such small variations in pressure, thus causing a disturbance in, rather than a correction of, the conditions.

The step-by-step regulator of the present invention, on the other hand, makes no attempt to regulate for such small fluctuations of pressure. The damper is maintained stationary, notwithstanding such small fluctuations, and is not moved until the pressure variation has become built up or down to a 45 sufficiently large value to indicate a permanently rising or a permanently falling load. Then, and then only, will the circuit of the electro-magnetic devices for actuating the pilot valve become closed. Then, and then only, will the damper be actuated by the hydraulic motor, and it will not be permitted to float back and forth but it will be moved through a certain distance or step, and there normally stopped. It will be 50 stopped because, as soon as the motor is started, it immediately opens the circuit of the electro-magnets, but the motor and, therefore, the damper, continues operating throughout a definite distance or step by virtue of the dashpots 16, 17. These dash-

pots introduce the necessary time lag to ensure the operation of the motor throughout the complete step. A further large change in pressure in one direction or the other must take place before the damper will again be 70 actuated, and it will then again be moved throughout a step, and then again stopped. The damper is brought to a stop at the end of certain distances or steps of movement, and is maintained against movement, or non- 75 responsive, at the end of each step until the pressure has changed sufficiently to cause a new step of movement. The damper is thus operated by steps in response to comparatively large variations in pressure and is 80 stopped at the end of each step, where it remains in position until there is a further predetermined variation in pressure, when the operation is repeated. These steps may 85 previously be designed so as to harmonize most closely with the demands of the particular plant under consideration.

Ordinarily, and normally, the steps of travel will be of substantially equal length. In fact, in some types of step-by-step regulators now on the market, each step of travel is fixed in length and position. According to the present invention, however, it is some times possible, under abnormal conditions, 90 for the length of the steps to become automatically slightly increased in accordance with the requirements of such abnormal conditions.

A few words will make clear the distinction between normal and abnormal operating conditions. It has been tacitly assumed, in the foregoing description, that the pressure changes take place comparatively slowly and gradually, as is actually the case under normal operating conditions. When 100 the pressure was described as rising from 100 to 101 pounds, causing contact to be made between the contact member (9) and the contact disc (27), the pressure rise was considered to be sufficiently slowly so that contact would be broken again immediately 105 as soon as the contact disc (27) was started moving upward.

Under abnormal operating conditions, 110 however, the pressure might rise so rapidly or abruptly as to cause the contact member (9) to move upward as fast as, or even faster than, the upward movement of the contact disk (27). In that event, contact between the contact disk (27) and the contact member (9) will be maintained, notwithstanding 115 the upward movement of the contact disk (27). The length of the step will then depend upon how soon contact is broken between the contact member (9) and the contact disk (27). And the same is true when 120 the pressure becomes decreased comparatively rapidly. In fact, if the boiler should burst, the contact member (8) would maintain contact with the contact disk (27) un- 125 130

til the motor has completed its full stroke, and the damper might be moved in a single stroke from full open to full shut.

Even when the steps are of unequal length, however, there will not be any hunting, or overtravel; for if a particular step of travel happens to be longer than a preceding step, it is because the abnormal conditions that caused it require a step of travel of such increased length. The regulator of the present invention, therefore, has some advantages over the absolutely-fixed-step regulators above described, but these advantages are balanced by greater complications in structure and increased sensitivity in operation, neither of which is always desirable.

The term "step-by-step operation", or its equivalent, is employed herein in the specification and claims to define an operation as described above, in which the definite completion of each particular step, as determined by boiler or other load conditions, is normally assured, but without hunting,—that is, without overtravel of the regulator, or travel to points beyond what is required by such boiler or other load conditions. The use of such term, as so defined, excludes from within its scope the old floating-type regulators, but without involving circumlocution of language.

Although I have described my invention in connection with regulation of dampers, I do not wish to limit its use, but to claim it broadly, as regulators of this class are used for a variety of purposes, such as the operation of valves for controlling the speed of fan engines, and turbo blowers, the operation of rheostats to control the speed of electric motors driving forces or induced pressure fans, the controlling of lever valves to reduce and regulate steam or other fluids under pressure and for other purposes. Nor is the invention necessarily restricted strictly to pressure systems, as it is equally applicable, for example, to temperature-control regulators.

Having fully described my invention, what I claim as new and desire to secure by Letters Patent of the United States, is:—

50. 1. The combination with a valve and a motor adapted to be operated thereby, of electromagnetic means for controlling the valve, means for energizing the electromagnetic means to effect the operation of the valve, and means controlled by the motor for deenergizing the electromagnetic means, thereby rendering the valve ineffective, upon the motor commencing to operate.

60. 2. The combination with a motor and a valve for operating the same having a neutral position in which it is ineffective and two effective positions in each of which it controls the direction of operation of the motor, electromagnetic means for actuating the valve to one or the other of its effective

positions, and means controlled by the motor for returning the valve to its neutral position upon the motor commencing to operate.

3. The combination of a valve arranged to normally assume a neutral position and to control the flow of fluid through said valve by being moved out of its neutral position, a rocker arm, a plurality of electromagnets, means pivotally connecting the electromagnets with the arm, the pivotal connections serving as fulcrum points for the rocker arm, and arrangements whereby the rocker arm is held stationary at each of said pivotal connections while the opposite magnet is operated to move the valve in a certain direction from its neutral position.

4. In a damper regulator, the combination of a motor for operating the damper, a pilot valve for operating the motor, electric magnets for operating the pilot valve, one magnet controlling the upward movement of the motor and the other magnet controlling the downward movement of the motor, a pressure operated circuit closer for independently operating the magnets, and a movable contactor controlled by the movement of the motor for breaking the circuit and causing the pilot valve to assume a neutral position and bring the motor to rest.

5. In a damper regulator the combination of a motor for operating the damper, a pilot valve for operating the motor, electric magnets for operating the pilot valve, one magnet controlling the upward movement of the motor and the other magnet controlling the downward movement of the motor, a pressure operated circuit closer for independently operating the magnets, and a contact disc threadably mounted on a screw spindle and revolvable by the movement of the motor for breaking the circuit and causing the pilot valve to assume a neutral position and bring the motor to rest.

6. In a pressure system, the combination with means comprising a valve having a stem adapted to occupy a neutral position in which the valve is ineffective and two effective positions in which the valve is adapted to control an increase and a decrease respectively in the pressure in the system, two electromagnets for respectively actuating the valve stem to its effective positions, a contact disk electrically connected to the electromagnets, a pressure chamber connected to the pressure system having a diaphragm, a scale beam connected to the diaphragm, whereby the movements of the beam are rendered responsive to the values of said pressure, a spindle connected to the scale beam, contact members respectively electrically connected to the electromagnets secured to the spindle upon opposite sides of the contact disk, whereby the electromagnets become respectively energized to effect the operation of the valve stem to its respective effective

positions upon the respective contact members contacting with the contact disk in response to the scale beam being moved in one or the other direction, and means controlled by the valve for separating the contact disk from its contacting contact member upon the commencement of the operation of the valve to cause the return of the valve stem to its neutral position.

10 7. In a pressure system, the combination with means comprising a valve for controlling the pressure in the system, of electromagnetic means having a plurality of armatures positively connected to the valve for actuating the valve in different directions, and means controlled in accordance with the pressure in the system for energizing the electromagnetic means to selectively actuate the armatures.

15 8. In a pressure system, the combination with means comprising a valve for controlling the pressure in the system, of an electromagnet having an armature positively connected to the valve for actuating the valve, a scale beam responsive to the pressure in the system, means connected to the scale beam for controlling the electromagnet, and means controlled by the valve for rendering the scale-beam-connected means ineffective.

20 9. In a pressure system, the combination with means comprising a valve having a stem adapted to occupy a neutral position in which the valve is ineffective and two effective positions in which the valve is adapted to control an increase and a decrease respectively in the pressure in the system, of electromagnetic means for selectively actuating the stem to its effective positions, means responsive to the pressure in the system for controlling the electromagnetic means and means controlled by the valve for rendering the electromagnetic means ineffective.

25 10. In a pressure system, means for controlling the pressure in the system, electromagnetic means for operating the controlling means, the controlling means being effective only while operated upon by the electromagnetic means, means responsive to the pressure in the system for rendering the electromagnetic means effective to operate the controlling means, and means for rendering the electromagnetic means ineffective to further operate the controlling means upon a predetermined limited operation of the controlling means.

30 11. In a pressure system, the combination with a motor for controlling the pressure in the system and a valve for controlling the motor, of electromagnetic means for controlling the valve, the valve being effective to control the motor only while operated upon by the electromagnetic means, means responsive to the pressure in the system for

35 rendering the electromagnetic means effective to control the valve, and means for rendering the electromagnetic means ineffective to further control the valve upon a predetermined limited operation of the motor.

40 12. In a pressure system, the combination with a motor operable to control the pressure in the system, of electromagnetic means for effecting the operation of the motor, means responsive to the pressure in the system for rendering the electromagnetic means effective, and means for rendering the electromagnetic means ineffective to further operate the motor, thereby bringing the motor to rest, upon a predetermined limited operation of the motor.

45 13. In a pressure system, the combination with a motor for controlling the pressure in the system, and a valve having a neutral position in which it is ineffective and an effective position in which the operation of the motor is effected, of electromagnetic means responsive to the pressure in the system for actuating the valve to the effective position, and means for returning the valve to the neutral position and effecting a stopping of the motor upon a predetermined limited operation of the motor.

50 14. In a pressure system, the combination with a fluid motor for controlling the pressure in the system, and a normally closed valve adapted, when open, to admit fluid under pressure to the motor, of electromagnetic means operable in accordance with the pressure in the system to control the valve, and means for rendering the electromagnetic means ineffective, and thereby permitting the closing of the valve and effecting a stopping of the motor, upon a predetermined limited operation of the motor.

55 15. In a pressure system, the combination with a motor operable to control the pressure in the system, and a valve having a neutral position in which it is ineffective and two effective positions in which it controls the operation of the motor in opposite directions, electromagnetic means for selectively actuating the valve to its effective positions, means responsive to the pressure in the system for controlling the electromagnetic means, and means controlled by the motor for rendering the electromagnetic means ineffective, thereby causing the valve to assume the neutral position and effecting a stopping of the motor.

60 16. In a pressure system, the combination with a motor for controlling the pressure in the system, a valve for controlling the motor, and a scale beam responsive to the pressure in the system, of electromagnetic means for controlling the valve, means controlled by the scale beam for rendering the electromagnetic means effective to control the valve, and means controlled by the motor for ren-

- dering the electromagnetic means ineffective to further control the valve upon a predetermined limited operation of the motor.
17. In a pressure system, the combination with a motor for controlling the pressure in the system having a range of operation between predetermined limits, and a valve for controlling the motor, of electromagnetic means for controlling the valve, the valve being effective to control the operation of the motor only when the electromagnetic means is effective to control the valve, means operable upon a variation in pressure in the system to render the electromagnetic means effective, and means operable to render the electromagnetic means ineffective, thereby rendering the valve ineffective and stopping the motor, upon a predetermined limited operation of the motor.
18. The combination with a movable member adapted normally to occupy a neutral position, of electromagnetic means for selectively moving the member to one side or the other of the neutral position, means for energizing the electromagnetic means to effect the selective movement of the member, and means for deenergizing the electromagnetic means, the member being adapted thereupon to return to the neutral position.
19. In a pressure system, the combination with means comprising a valve having a stem adapted to occupy a neutral position in which the valve is ineffective and two effective positions in which the valve is adapted to control an increase and a decrease respectively in the pressure in the system, means controlled by the pressure in the system for selectively actuating the stem to its effective positions, and means controlled by the valve for rendering the pressure-controlled means ineffective upon the valve-controlled means commencing to operate.
20. In a pressure system, a motor for controlling the pressure in the system, a valve for controlling the motor, a scale beam for controlling the valve, a diaphragm controlled in accordance with the pressure in the system connected to the scale beam, and means connected to the motor whereby the valve is operated to control the operation of the motor step by step.
21. In a regulator comprising a motor and a pressure-responsive device, a controlling element for said motor, and means operated by the motor and the pressure-responsive device for effecting an intermittent control of said controlling element, for effecting the operation of the motor step by step.
22. In a regulator comprising a motor and a pressure-responsive device, a controlling element for said motor, and auxiliary motive means operated by the pressure-responsive device and the motor for effecting an intermittent control of the controlling element, whereby the motor is operated in abrupt steps.
23. In a regulator comprising a motor and a pressure-responsive device, a controlling element for said motor, means operated by the pressure-responsive device for abruptly operating the controlling element to operate the motor, and means operated by the motor including a time-lag element for controlling the controlling element, whereby the motor is operated in predetermined stages of travel with a well defined period of rest between said stages.
24. In a regulator comprising a motor and a pressure-responsive device, a controlling element for said motor, means operated by the motor and the pressure-responsive device including a time-lag element for intermittently controlling the controlling element to effect a step-by-step control of the motor.
25. In a regulator comprising a motor and a pressure-responsive device, a controlling element for said motor, and auxiliary motive means operated by the pressure-responsive device and the motor including a time-lag element for intermittently controlling the controlling element to effect a step-by-step control of the motor.
26. In a regulator comprising a motor and a pressure-responsive device, means to control the operation of said motor in opposite directions, said means including two electromagnets, one of said magnets controlling the operation of the motor in one direction and the other magnet controlling the operation of the motor in the opposite direction, a pilot switch in circuit with said magnets and controlled by the pressure-responsive device, said pilot switch being arranged to make an electric contact on variations in pressure acting on the pressure-responsive device to operate either one or the other magnet, and means operated by the motor for breaking said contact after the motor has operated for a predetermined period.
27. In a regulator comprising a motor and a pressure-responsive device, a controlling element for said motor, auxiliary motive means for operating the controlling element, and means jointly controlled by the motor and the pressure-responsive device for controlling said auxiliary motive means.
28. In a pressure regulator, in combination, a pressure-responsive device, a motor for controlling the pressure to which the pressure-responsive device is adapted to be subjected, a valve for controlling the motor, means operated in accordance with variations in the said pressure to effect an abrupt operation of the valve to open position to effect operation of the motor, and means operated by the motor for closing the valve to render the motor ineffective.
29. A regulator having, in combination, a

pressure-responsive device, a motor for controlling the pressure to which the pressure-responsive device is adapted to be subjected, a valve for controlling the motor, and means controlled by the pressure-responsive device and the motor for effecting the opening and the closing of the valve to effect the operation of the motor step by step.

30. A regulator having, in combination, a motor, a device controlled by the motor, means for rendering the motor effective to control the device, and means controlled by the motor for rendering the first-named means ineffective, the said several means co-operating to effect the operation of the motor step by step.

31. A regulator having, in combination, a pressure-responsive device, a motor for controlling the pressure to which the pressure-responsive device is adapted to be subjected, two elements having two relatively effective positions in which they are adapted to control the operation of the motor in opposite directions and a relative neutral position in which they are ineffective, and means controlled by the pressure-responsive device and the motor for relatively actuating the elements to the relative effective and to the relative neutral positions to effect the operation of the motor step by step.

32. A regulator having, in combination, a pressure-responsive device, a motor for controlling the pressure to which the pressure-responsive device is adapted to be subjected, an element having two effective positions in which it is adapted to control the operation of the motor in opposite directions and a neutral position in which it is ineffective, means controlled by the pressure-responsive device for actuating the element to the effective positions, means controlled by the motor for actuating the element to the neutral position, and means for rendering the operation of the element to one of the said positions abrupt.

33. A regulator having, in combination, a pressure-responsive device, means for controlling the pressure to which the pressure-responsive device is adapted to be subjected, electromagnetic means having a plurality of armatures positively connected to the pressure-controlling means for actuating the pressure-controlling means in different directions, and means controlled by the pressure-responsive device for energizing the electromagnetic means to selectively actuate the armatures.

34. A regulator having, in combination, a pressure-responsive device, a motor for controlling the pressure to which the pressure-responsive device is adapted to be subjected, an element for controlling the motor, means controlled by the pressure-responsive device for operating the element in one direction to effect the operation of the motor, means

controlled by the motor for operating the element in another direction to effect a stopping of the motor, and means for ensuring a predetermined degree of operation of the motor before the motor is stopped.

35. A regulator having, in combination, a pressure-responsive device, a motor for controlling the pressure to which the pressure-responsive device is adapted to be subjected, an element for controlling the motor, means controlled by the pressure-responsive device for operating the element intermittently in one direction to effect a step-by-step operation of the motor, means controlled by the motor for operating the element intermittently in another direction to successively terminate the steps of operation of the motor, and means for ensuring that the motor shall operate to a predetermined degree at each step of its operation before the motor is stopped at the end of each step of its operation.

36. A regulator having, in combination, a pressure-responsive device, a motor for controlling the pressure to which the pressure-responsive device is adapted to be subjected, a valve for controlling the motor, means controlled by the pressure-responsive device for operating the valve in one direction, means controlled by the motor for operating the valve in another direction, and means for rendering the operation of the valve in one of the said two directions abrupt.

37. A regulator having, in combination, a pressure-responsive device, a motor for controlling the pressure to which the pressure-responsive device is adapted to be subjected, a valve for controlling the motor, means controlled by the pressure-responsive device for opening the valve, means controlled by the motor for closing the valve, and means for rendering one of the said two operations of the valve abrupt.

38. A regulator having, in combination, a pressure-responsive device, a motor for controlling the pressure to which the pressure-responsive device is adapted to be subjected, an element for controlling the motor, means controlled by the pressure-responsive device for operating the element in one direction, means controlled by the motor for operating the element in another direction, and means for rendering the operation of the element in one of the said two directions abrupt.

39. A regulator having, in combination, a pressure-responsive device, a motor for controlling the pressure to which the pressure-responsive device is adapted to be subjected, an element having two effective positions in which it is adapted to control the operation of the motor in opposite directions and a neutral position in which it is ineffective, means controlled by the pressure-responsive device for actuating the element to the effective positions to effect the operation of the

motor in opposite directions, means controlled by the motor for actuating the element to the neutral position to effect a stopping of the motor, and means for ensuring a predetermined degree of operation of the motor before the motor is stopped.

40. A regulator having, in combination, a pressure-responsive device, a motor for controlling the pressure to which the pressure-responsive device is adapted to be subjected, an element having two effective positions in which it is adapted to control the operation of the motor in opposite directions and a neutral position in which it is ineffective, means controlled by the pressure-responsive device for selectively actuating the element intermittently to the effective positions to effect a step-by-step operation of the motor, means controlled by the motor for actuating the element intermittently to the neutral position to successively terminate the steps of operation of the motor, and means for ensuring that the motor shall operate to a predetermined degree at each step of its operation before the motor is stopped at each step of its operation.

41. In apparatus for automatic draft control, a draft regulator, impelling means therefor, a motor for driving the same in either of two directions, controlling means for causing step by step movement of said motor in either direction, a pressure motive mechanism capable of acting in any position of the impelling means to operate said controlling means, and a source of pressure dependent upon the draft regulated for actuating said pressure motive mechanism.

42. A draft regulator having, in combination, means operable in either of two directions for regulating the draft, a motor for actuating the draft-regulating means in either of the said two directions, a pressure device the pressure upon which is controlled by the draft, controlling means for causing step-by-step operation of the regulating means by the motor in either of the said two directions, and means controlled by the pressure device and operable independently of the motor for operating the controlling means.

43. In a fluid system in which the condition of the fluid in the system is controlled by a draft, a motor operable in either of two directions for regulating the draft, a pressure device the pressure upon which is controlled in accordance with the condition of the fluid in the system, controlling means for causing step-by-step operation of the motor in either of the said two directions, and means controlled by the pressure device and operable independently of the motor for operating the controlling means.

44. In a draft-control regulator for boilers, means operable in either of two directions for regulating the draft, a motor for driving

the draft-regulating means in either of the said two directions, the motor being adapted to occupy a plurality of positions each corresponding to a predetermined value of the boiler load, an element for controlling the starting of the motor in either direction, means controlled in accordance with variations in the boiler load for actuating the element to effect the starting of the motor in either direction, means for preventing the motor from starting until the said variations attain a predetermined value, and means for normally stopping the motor when the motor has been actuated to a position corresponding to the value of the boiler load at which the motor started, whereby the motor is operable step by step to operate the draft-regulating means step by step.

45. In a fluid system, a motor for controlling the condition of the fluid in the system, the motor being adapted to occupy a plurality of positions each corresponding to a predetermined value of the condition of the fluid in the system, an element for controlling the starting of the motor, a pressure device the pressure upon which is controlled in accordance with variations in the condition of the fluid in the system, means controlled by the pressure device for actuating the element to effect the starting of the motor, means for preventing the motor from starting until the said variations attain a predetermined value, and means for normally stopping the motor when the motor has been actuated to a position corresponding to the value of the condition of the fluid in the system at which the motor was started, whereby the motor is operable step by step.

46. In a fluid system, a motor for controlling the condition of the fluid in the system, the motor being adapted to occupy a plurality of positions each corresponding to a predetermined value of the condition of the fluid in the system, two elements having a relative neutral position in which they are ineffective and a relative effective position in which they effect the starting of the motor, means controlled in accordance with variations in the condition of the fluid in the system for relatively actuating the elements to the relative effective position when the said variations attain a predetermined value to effect the starting of the motor, and means for normally relatively returning the elements to the relative neutral position to stop the motor when the motor has been actuated to a position corresponding to the value of the condition of the fluid in the system at which the motor was started, whereby the motor is operable step by step.

47. In combination, a pressure device, a motor for controlling the pressure upon the pressure device, the motor being adapted to occupy a plurality of positions each corre-

sponding to a predetermined value of the pressure upon the pressure device, an element for controlling the starting of the motor, means controlled in accordance with variations in the pressure upon the pressure device for actuating the element to effect the starting of the motor, means for preventing the motor from starting until the said variations attain a predetermined value, and 5 means for normally stopping the motor when the motor has been actuated to a position corresponding to the value of the pressure upon the pressure device at which the motor was started, whereby the motor is operable step by step.

48. In combination, a pressure device, a motor for controlling the pressure upon the pressure device, the motor being adapted to occupy a plurality of positions each corresponding to a predetermined value of the pressure upon the pressure device, two elements having a relative neutral position in which they are ineffective and two relative effective positions in which they control the starting of the motor in opposite directions, means controlled in accordance with variations in the pressure upon the pressure device for relatively actuating the elements to the relative effective positions when the said 20 variations attain a predetermined value to effect the starting of the motor in one or the opposite direction, and means for normally relatively returning the elements to the relative neutral position to stop the motor when the motor has been actuated to a position corresponding to the value of the pressure upon the pressure device at which the motor was started, whereby the motor is operable step by step.

49. In a fluid system, a motor for controlling the condition of the fluid in the system, a valve for controlling the motor, and means controlled in accordance with the condition of the fluid in the system for opening and closing the valve to effect a step-by-step operation of the motor.

50. In a fluid system, a motor for controlling the condition of the fluid in the system, two elements having a relative neutral position in which they are ineffective and a relative effective position in which they control the operation of the motor, means controlled in accordance with the condition of the fluid in the system for relatively actuating the elements to the relative effective position, and means for relatively returning the elements to the relative neutral position at stepped points in the operation of the motor to effect step-by-step operation of the motor.

51. In combination, a pressure device, a motor operable step by step to control the pressure upon the pressure device, two elements for controlling the motor having a relative neutral position in which they are

ineffective and two relative effective positions in which they control the operation of the motor in opposite directions, means controlled by the pressure device for actuating the elements to the relative effective positions, and means for returning the elements to the relative neutral position at stepped points in the operation of the motor to effect a step-by-step operation of the motor.

52. In a pressure system, a motor operable in either of two directions for regulating the pressure in the system, controlling means for causing step-by-step operation of the motor in either of the said two directions, and means controlled in accordance with the pressure in the system and operable independently of the motor for operating the controlling means.

53. In a pressure system, means operable in either of two directions for regulating the pressure in the system, a motor for actuating the regulating means in either of the said two directions, controlling means for causing step-by-step operation of the regulating means by the motor in either of the said two directions, and means controlled in accordance with the pressure in the system and operable independently of the motor for operating the controlling means.

54. In a fluid system, means operable in either of two directions for regulating the condition of the fluid in the system, a motor for actuating the regulating means in either of the said two directions, a pressure device the pressure upon which is controlled in accordance with the condition of the fluid in the system, controlling means for causing step-by-step operation of the regulating means by the motor in either of the said two directions, and means controlled by the pressure device and operable independently of the motor for operating the controlling means.

55. In a fluid system, means for controlling the condition of the fluid in the system, means controlled in accordance with the condition of the fluid in the system for starting the operation of the controlling means, means controlled by the controlling means for stopping the operation of the controlling means, and time-lag means for delaying the stopping of the operation of the controlling means.

56. In a fluid system, means for controlling the condition of the fluid in the system, electric means for starting the operation of the controlling means, a switch for controlling the electric means, means controlled in accordance with the condition of the fluid in the system for closing the switch to cause the electric means to effect the starting of the operation of the controlling means, means controlled by the controlling means for opening the switch to effect the stopping of the operation of the controlling means,

and time-lag means for delaying the stopping of the operation of the controlling means.

57. In apparatus for automatic draft control, a motor operable in either of two directions for regulating the draft, controlling means for causing step-by-step operation of said motor in either of the said two directions, a pressure mechanism the pressure upon which is controlled by the draft, and means controlled by the pressure mechanism and operable independently of the motor for operating said controlling means.

58. In a pressure system, means operable in either of two directions for regulating the pressure in the system, a motor for actuating the regulating means in either of the said two directions, the motor being adapted to occupy a mean average position when the pressure in the system has a mean average value, a pressure device responsive to the pressure in the system, controlling means controlled in accordance with variations in the pressure of the system for causing step-by-step operation of the regulating means by the motor in either of the said two directions, and means controlled by the pressure device and operable independently of the motor for operating the controlling means when the said variations attain a predetermined value.

59. In a pressure system, a reversible motor for regulating the pressure in the system and adapted to occupy a mean average position when the pressure in the system has a mean average value, a pressure device responsive to the pressure in the system, controlling means controlled in accordance with variations in the pressure of the system for causing step-by-step operation of the motor in either of its two opposite directions of operation, and means controlled by the pressure device and operable independently of the motor for operating the controlling means when the said variations attain a predetermined value.

60. In a pressure system, a reversible motor for regulating the pressure in the system and adapted to occupy a mean average position when the pressure in the system has a

mean average value and to occupy a plurality of other positions each corresponding to a predetermined value of the pressure, an element for controlling the starting of the motor in either of its two opposite directions of operation, and means controlled in accordance with variations in the pressure of the system for actuating the element to effect the starting of the motor in either of its two opposite directions of operation, for preventing the motor from starting until the said variations attain a predetermined value, and for stopping the motor when the motor has been actuated to a position corresponding to the value of the pressure at which the motor started.

61. In a pressure system, a motor for controlling the pressure in the system, pressure-controlled means for causing a step-by-step operation of the motor, and time-lag means for ensuring the completion of the steps of operation.

62. In a pressure system, a reversible motor for controlling the pressure in the system and adapted to occupy a mean average position where the pressure in the system has a mean average value, a governing element for the motor, means controlled in accordance with variations in the pressure of the system for operating said element to cause a step-by-step operation of said motor in either direction, and time-lag means for ensuring the completion of the steps of operation.

63. In a boiler-control system having a furnace and a boiler, means operable in either of two directions for controlling the draft to the furnace, a motor for actuating the controlling means in either of the said two directions, and means for effecting step-by-step operation of the controlling means by the motor in either of the said two directions by steps of substantially equal length under normal conditions and by steps of automatically varying length under abnormal conditions.

In testimony whereof I have affixed my signature.

JAMES LEWIS KIMBALL.
